UNITED STATES PATENT OFFICE.

DAVID LAZAR, OF BROOKLYN, NEW YORK.

COIN-CONTROLLED VENDING MACHINE.

Application filed August 3, 1922. Serial No. 579,387.

This invention relates to coin controlled vending machines especially adapted for use in restricted places and has for an object the provision of a machine which may be attached to the backs of seats in theaters, halls and other places of like character for the purpose of vending articles such as candy and the like.

To this end, the invention aims to provide a vending machine from which all projecting members, such as operating knobs, compartment closures, locking devices or like objectionable features have been eliminated, so as to prevent injury to the garments of persons passing between the seats.

Another object of the invention is the provision of a coin controlled machine from which the operating mechanism may be removed as a unit, so that a damaged mechanism may be removed and another substituted within a relatively short time and with a minimum amount of labor and thus avoid the necessity of repairing the machine within the restricted space provided between the rows of seats, the mechanism being further constructed so that the machine must be empty to permit of the said mechanism being replaced.

Another object of the invention is the provision of means for automatically closing the coin chute to prevent the insertion of a coin before a previously inserted coin acts to release the article being vended, whereby interference with the operation of the machine from this cause will be prevented.

Another object of the invention is the provision of means whereby an article or a coin other than the proper operating coin, will, when inserted within the coin chute, be returned without operating the delivering mechanism.

Another object of the invention is the provision of a machine of the above character which includes a cover capable of being removed without disturbing the operating mechanism, whereby the latter may be conveniently inspected.

A further object of the invention is the provision of a vending machine which may be locked only by means of a special key, so that annoyance occasioned by empty machines, or those filled with paper or other foreign articles may be avoided, enabling the attendant to determine at a glance the machines needing refilling.

With the above and other objects in view, the invention further includes the following novel features and details of construction, to be hereinafter more fully described, illustrated in the accompanying drawings and pointed out in the appended claim.

In the drawings:—

Figure 1 is a front elevation of a vending machine constructed in accordance with the invention.

Figure 2 is a similar view with the cover of the machine removed.

Figure 3 is a rear elevation of the removable mechanism unit.

Figure 4 is an elevation of the attaching frame.

Figure 5 is a section on the line 5—5 of Figure 1.

Figure 6 is a section on the line 6—6 of Figure 2 with the cover in place.

Figure 7 is a similar view on the line 7—7 of Figure 2.

Figure 8 is a section on the line 8—8 of Figure 2.

Figure 9 is a detail perspective view of the coin ejecting plunger.

Figure 10 is a fragmentary view illustrating the means of closing the same.

Figure 11 is a detail section showing a modified form of compartment closure.

Figure 12 is a detail view of the cover lock.

Figure 13 is a detail view of the closure locking key.

Figure 14 is a detail view of the key for locking the removable cover.

Referring in detail to the drawings, wherein like characters of reference denote corresponding parts, the reference character 20 indicates a support, such as the back of a chair in a theater or other public place and to which the invention is shown as attached. The invention includes an attaching frame 21, which is substantially rectangular in shape and which is secured to the support 20 by means of screws 22 and spacing sleeves 23, so that the face 24 of the attaching frame will be spaced from the support 20. This frame has removably secured thereto what will be hereinafter referred to as a mechanism unit, indicated in its entirety by the reference character 25, the said unit carrying all of the operating mechanism of the machine so that when necessary, this mechanism may be easily and quickly removed and a new mechanism sub-

stituted. The mechanism unit 25 includes a plate 26 which carries all of the operating mechanism and which in addition, carries the article compartments 27 which are two in number and spaced apart. This plate 26 has extending from its rear face headed studs or screws 28, which are adapted to engage within key-hole slots 29 provided in the outer face 24 of the frame 21. A screw 30 passing through the plate 26 and engaging a threaded opening 31 provided in the frame 21, serves to hold the mechanism unit 25 in place. By removing the screw 30, the unit 25 may be quickly detached and another substituted, so that any machines out of order may be conveniently restored within the limited time provided between performances in a theater or other place of amusement.

The article compartments 27 are as previously stated, spaced apart and are provided with longitudinally disposed slots 32 in their outer walls and at their tops with removable covers or closures 33, the latter being slidable through slots 34 provided in the plate 26 and when in open position, these covers or closures will occupy a space at the rear of the plate 26 so as to leave an unobstructed open top for the ejection of a vended article, (not shown). The upper edge of the slot 34 is offset as shown at 35 so as to facilitate the passage of the closure 33 therethrough and permit the same to fall behind the plate 26, where its downward movement will be limited by means of a stop 36, springs 37 attached to the closure 33 serving to force the latter downward. One edge of the closure 33 is provided with a lip 38 which engages the lower edge of the slot 34 when the closure is in open position, while extending from the top of the closure near the opposite edge thereof is a flange 39 which engages the stop 36.

The closures 33 are held in closed position by means of a locking spring 40, the latter being provided with a lug 41 which engages beneath the rear edge of the closure 33. This locking spring is secured to the rear face of the plate 26 as shown at 42 and operating beneath the upper free end of the spring is a rocker bar 43 whose opposite ends are mounted in bearing lugs 44. The bar 43 is provided with a lug 45 which, when said bar is rocked, is adapted to engage the spring 40 to release the lug 41 from engagement with the closure 33 and permit the latter to open under the influence of the spring 37.

Extending from each of the rocker bars 43 is an arm 46 which is engaged by an offset portion 47 of a vertically movable rod 48 which is slidable in bearing lugs 49 carried by the plate 26. The lower ends of the rods 48 bear upon the edges of spaced cams 50 which are rotatable upon a shaft 51 and

which are yieldingly forced downward upon these cams by means of a spring 52, the latter also serving to resist pivotal movement of the rocker bar 43 and consequently resisting upward movement of the rods 48. Adjacent each of the rocker arms 43 is a spring actuated trigger 53, which is adapted to engage lugs 54 so as to prevent engagement of the lug 45 with the spring 40, these triggers being provided with key engaging portions 55 which are adapted to be engaged by a key 56. By operating the key 56, the triggers 53 may be moved against the action of spring 57 so as to release them from beneath the lug 54 and permit the rocker bar 43 to release the springs 40, whereupon the latter will engage beneath the rear ends of the closures 33 so as to hold the latter in closed position. Ordinarily, in machines of this character, the package is utilized to lock the article compartments in closed position and unauthorized persons may then insert an empty package, or may stuff the compartment with paper so as to lock the same and an attendant is thus unable to determine which of the machines need refilling. This objection is obviated in the present machine by the requirement of a special key for locking the article compartment.

Each compartment is provided in its bottom with a spring actuated ejector member 58, having a spring 59 positioned between said member and the bottom of the compartment 32, so that when the closure 33 is released, the member 58 will be actuated to eject the article A.

Located between the compartments 32 is a coin chute 59' which is adapted to receive a coin of suitable denomination, for example a nickel. This coin passes downward through the chute and engages a stationary stop 60 and a movable stop 61, the said stops being normally spaced a distance less than the diameter of a nickel. The nickel is released by means of a plunger 62 which operates in a guide block 63 secured between the compartments 32 and to the outer wall of the coin chute 59'. In its downward movement, the coin passes a spring actuated coin ejecting dog 64 which rests above the upper edge of the coin when the latter engages the stops 60 and 61 and when the plunger is depressed in a manner hereinafter explained, the stop 61 will be moved to release the coin. When thus released, the coin will drop upon the upper edge of a pivotally mounted rocker arm 65, which is pivoted to the plate 26 at 66 and which is provided with a longitudinal flange 67 along its upper edge, the downward movement of the plunger 62 also serving to operate the rocker arm 65 to direct the coin into a coin receptacle 69 located at one corner of the plate 26. Due to the normally inclined

position of the rocker arm 65 as shown in Figure 2, a coin other than the proper actuating coin will not operate the movable stop 61, but will pass through between the stops 5 on to the rocker arm 65 and be directed to an opening 70 provided in a cover plate 71. This cover plate encloses the mechanism as will be hereinafter explained.

Extending downwardly from the plunger 62 is a projection 72 which carries at its lower end an offset slotted arm 73, whose slot receives a pin 74 carried by the rocker arm 65; thus when the plunger is depressed, the rocker arm will be pivotally moved so 15 as to direct the coin into the receptacle 69 as before stated. The upper end of the plunger 62 carries a head 75 having a finger socket 76 in one face thereof. Positioned between the heads 75 and shoulders 77 upon 20 the upper end of the guide block 63 are coiled springs 78 which act to normally force the plunger upward. The finger socket 76 is reached through an opening 79 provided in the cover 71. An apron 80 depends from the 25 head 75 and operates behind the opening 79 of the cover.

The movable stop 61 extends through an arcuate slot 81 provided in the plate 26 and is carried by a lever 82 which is pivotally 30 mounted upon the plate 26 as shown at 83. The opposite end of the lever 82 carries a spring pressed actuating dog 84 which engages the teeth of a ratchet wheel 85, so that when the proper coin forces the stop 35 61 outward or in a direction away from the stationary stop, the dog 84 will move the ratchet wheel 85 the distance of one tooth. A spring actuated holding dog 86 also engages the ratchet wheel 85 to insure proper 40 operation of the latter.

Pivottally mounted upon the lever 82 as shown at 87 is an arm 88, whose lower end has pivotally connected thereto as shown at 89, one end of a rod 90. The opposite end 45 of this rod is connected to one end of a crank arm 91 which extends through a slot 92 provided in the plate 26 and which is carried at the lower end of a rocker arm 91', the latter being mounted in suitable bearings 50 and being provided at its upper end with a right angularly disposed substantially L-shaped arm 93. The extremity of the arm 93 extends through an opening 93^a provided in the outer wall of the coin chute 59' and is adapted to extend across the mouth of this chute to prevent the insertion of a coin. 55 Pivottally secured to the coin chute is a spring actuated holding dog 94 which is adapted to engage beneath the extremity 60 of the arm 93 to prevent the latter from entering the coin chute.

The mechanism unit 26 is covered by the cover 71 and the latter is provided along its opposite edges with lugs 95 which engage 65 slots 96 provided in the attaching frame 21.

The upper edge of the cover 71 is recessed or cut away as shown at 97 so as to provide for the passage of vended articles and in addition, the upper edge of the cover is provided with a tongue 98 having a slot 99 70 therein which registers with the top of the open end of the coin slot to permit insertion of a coin. The tongue 98 is provided with a lug 100 which is adapted to engage within a slot 101 formed in the upper end of the 75 plate 26. The lower end of the cover is locked to the plate 26 by means of locking mechanism indicated generally at 102 and having an operating key 103.

In the operation of the invention, a coin is 80 inserted within the coin chute 59' and is forced downwardly past a pin 104 carried by the holding dog 94 and forces this dog from engagement beneath the extremity of the arm 93 so as to permit the latter to pass 85 into the coin chute through the slot 93^a under the action of a spring 105. This rocks the arm 91' and through the rod 90 brings the arm 88 into position to be engaged by the fulcrum 83 of the lever 82 when the latter 90 is actuated by the coin. The coin passes downward through the chute 59' and engages the stops 60 and 61, moving the dog 64 so that the latter will be positioned over 95 the upper edge of the coin. The plunger 62 is then moved downward to force the coin past the stops 60 and 61 and permit said coin to fall upon the rocker arm 65. This downward movement of the plunger will, 100 through the slotted arm and pin connection 73 and 74, incline the rocker arm 65 toward the coin receptacle so as to direct the coin into the said receptacle. Movement of the stop 61 under the action of the coin will 105 operate the lever 82 so that the dog 84 will move the ratchet wheel 85 the distance of one tooth. This movement of the lever 82 will cause the arm 88 to actuate the rocker arm 91' so as to withdraw the extremity of the arm 93 from the coin slot and leave the latter 110 free for the reception of another coin. Operation of the ratchet wheel 85 will carry with it the cams 50 and as these cams are arranged to alternately operate the slide rods 48, one of said rods will be actuated to operate the rocker bar 43 to move the locking spring 40 from engagement with one of the closures 33, whereupon the spring 37 of the latter will draw the closure downward into 115 open position and permit the member 58 to eject the article from one of the compartments. As the cams 50 are alternately arranged only one of the compartments will be opened, the other remaining closed until 120 actuated by the insertion of another coin. 125

In order to close the compartments 32 after the latter have been refilled there is provided a key 106 which is illustrated in Figure 10 of the drawings. This key is provided with a notch 107 for engagement over 130

either of the studs 28 so as to provide a fulcrum for the key and the latter is inserted through a slot provided in the side of the cover 71 so as to engage beneath the closure 33 and lift the same against the action of the spring 37. Due to the offset edge of the slot 34, the closure will be guided horizontally over the upper end of the compartment.

In Figure 11 there is illustrated a modified form of closure which is hingedly mounted at the upper end of the compartments as shown at 108 and which is provided with a lug 109 which is adapted to engage the upper end 41 of the locking spring 40 in the manner previously described. The cover is moved to an open position by means of a spring as previously described and its operation is the same as that described in connection with the preceding form of cover.

The invention is susceptible of various changes in its form, proportions and minor details of construction and the right is herein

reserved to make such changes as properly fall within the scope of the appended claim.

Having described the invention what is claimed is:

A coin controlled vending machine embodying article compartments, closures for said compartments, means consisting of spring arms operatively associated with said closures to retain them in closed positions, rockable members having devices engageable with said spring arms to release said closures, resilient means under tension for actuating the closures when released, coin controlled means embodying longitudinally movable rods operatively associated with the rockable members, and cams operatively associated in connection with the longitudinally movable rods, whereby the rockable members may independently and alternately operate to alternately open the article compartments.

In testimony whereof I affix my signature.

DAVID LAZAR.
